UNITED STATES PATENT OFFICE.

SAMUEL SMITH, OF SILVER LAKE, INDIANA, ASSIGNOR OF TWO-THIRDS TO
ANDREW D. HOMMAN AND HENRY D. PONTIUS, BOTH OF SAME PLACE.

HEATING ATTACHMENT FOR STOVES.

SPECIFICATION forming part of Letters Patent No. 349,534, dated September 21, 1886.

Application filed March 9, 1886. Serial No. 194,548. (No model.)

To all whom it may concern:

Be it known that I, SAMUEL SMITH, a citizen of the United States, and a resident of Silver Lake, in the county of Kosciusko and State of Indiana, have invented certain new and useful Improvements in Heating Attachments for Stoves; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a portion of a stove-pipe provided with my improved heating attachment; and Fig. 2 is a vertical sectional view of the same, taken through two of the pipes.

Similar letters of reference indicate corresponding parts in both the figures.

My invention has relation to that class of heating attachments for stove-pipes in which two conical chambers fit upon sections of the stove-pipe, and are connected by means of a number of pipes opening in the bases of the conical chambers, the stove-pipe sections entering the apices of the conical chambers; and it consists in the improved construction and combination of parts of the same, as herein-30 after more fully described and claimed.

In the accompanying drawings, the letters A A indicate the two portions of stove-pipe, upon which fit portions B and C of pipe, which respectively enter the apices of the upper and lower conical chambers, D and E, which have their bases facing each other. The upper section, B, of pipe is provided with a damper, F, of the usual construction, by means of which the draft in the pipe and en-40 tire heating apparatus may be regulated, as in stove-pipes of the usual construction without heating attachment. The edges G of the bases of the conical chambers are bent over the flanged edges of the tapering sides of the same, the said edges and flanges, which latter are lettered H, forming tight and simple joints between the sides and bases of the chambers. The bases of the chambers are formed

with perforations I, arranged so that the perforations in both bases register with each other, and the tubes J, or flues which connect the bases and chambers, fit with their ends in these apertures. The upper and lower ends of these flues, where they fit into the apertures, are formed tapering or conical, so as to fit snugly in the apertures, and the bases of the two chambers are connected by means of a rod, K, which serves to draw the bases of the chambers toward each other, and to draw the apertures firmly upon the conical ends L 50 of the flues. This rod is preferably composed of two parts, which are formed with right and left hand threaded ends, upon which a correspondingly threaded nut, M, fits, so that by turning the nut the chambers may be 55 drawn toward each other, the rods being secured in the centers of the bases of the chambers.

It will be seen that as the smoke and heat and other products of combustion pass up 70 through the stove-pipe they will be retained and spread over a comparatively larger space in the chambers and flues, and come in contact with a larger surface than in the pipe, allowing the said products of the combustion to 75 give off their heat to the walls of the chambers and to the tubes, which will again radiate the heat into the room through which the pipe passes, and give off the heat to the air circulating between the flues and around the chambers, thus utilizing the heat, which otherwise would be wasted by passing up through the chimney into the air.

By tightening the nut upon the ends of the rods the joints between the flues and apertures 85 in the chambers may be tightened, as the conical ends of the flues will be forced more firmly into the apertures.

Having thus described my invention, I claim and desire to secure by Letters Patent of the 90 United States—

In a heating attachment for stove-pipes, the combination of two conical chambers having pipe-sections at the apices of the chambers, and having a number of registering apertures in their bases, a number of flues having 95

their ends tapering or conical and fitting in the apertures, and rods having right and left hand screw-threaded ends and secured at the centers of the bases of the chambers, and provided with a nut having corresponding threads fitting upon them, as and for the purpose shown and set forth.

In testimony that I claim the foregoing as my own I have hereunto affixed my signature in presence of two witnesses.

SAMUEL SMITH.
